UNITED STATES PATENT OFFICE.

GEORGE W. PELTON, OF MUSCATINE, IOWA.

CLAMP.

1,359,524.

Specification of Letters Patent. Patented Nov. 23, 1920.

Application filed March 15, 1920. Serial No. 366,025.

To all whom it may concern:

Be it known that I, GEORGE W. PELTON, a citizen of the United States, residing at Muscatine, in the county of Muscatine and State of Iowa, have invented a new and useful Clamp, of which the following is a specification.

This invention relates to wash board attachments, and it is an object of the invention to provide means adapted to be readily attached to a wash board to maintain the wash board in a predetermined position within a wash tub, during the washing operation.

10 A further object of the invention is to provide a device of this character which may be adjusted to various lengths, thus adapting the attachment for use in connection with wash tubs of various sizes.

15 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 illustrates a perspective view of a wash tub, having a washboard supported therein, the attachment being shown in its operative position.

Fig. 2 illustrates a side elevational view partly in section of the attachment.

Referring to the drawing in detail, the reference character 5 designates a wash tub 40 which is of the usual construction, the same being provided with the usual flange bottom 6.

Supported within the tub 5, is the washboard, indicated at 7, and as shown this washboard is positioned in its proper washing position, the upper end of the washboard extending beyond the plane of the side walls of the tub 5 to be engaged by the operator to prevent undue movement of the board with relation to the tub 5.

It has been found in practice that during the washing operation, the washboard 7 is continually working from its operative position, and to this end the attachment includes means for securing the washboard

against movement, under the washing operation.

A hook member 8, is positioned in the head of the washboard 7, preferably in the rear edge thereof, and at a point substantially intermediate the length of the head of the board so that the device will secure the washboard to prevent lateral movement thereof.

The body portion of the device is indicated at 9, and includes a length of metal having one of its ends turned in and lying in spaced relation with the body 9, as at 10, the opposite end of said body being disposed at right angles with relation to the side walls thereof, as at 11, which right angled portion is provided with a suitable aperture adapted to receive the hooked end 12 of the connecting rod 13.

This connecting rod 13 has a threaded 75 extremity 14, adapted to be positioned within one end of the relatively long coiled spring 15, whereby the coiled spring is connected with the rod 13. A screw eye 16 has the threaded portion thereof positioned 80 within the opposite end of the coiled spring 15, and in operation this screw eye 16 is positioned over the hooked member 8, so that when the hook member 10 of the body 9 is positioned under the flange 6 of the tub, 85 the coiled spring 15 is put under tension to hold the upper end of the washboard into close engagement with the upper edge of the wash tub 5.

If it is found desirable to employ the attachment in connection with a relatively shallow tub, it is of course obvious that the hook member 12 may be removed from its connection with the walls of the right angled portion 11, the hook member 12 being 95 now positioned in a predetermined opening of the body portion 9, the openings being indicated at 17 and disposed in spaced relation with each other throughout the length of the body 9.

From the foregoing it is obvious that the attachment may be employed in connection with tubs of various depths, by adjusting the hook member 12, and positioning the same within suitable openings of the body 105 portion 9.

Having thus described the invention, what I claim as new is:—

1. In combination, a washboard; a hook member secured to the washboard, an at- 110

tachment including a body portion having a hook member adapted to be positioned over the flanged bottom of a tub, a connecting rod having connection with the body portion, a 5 coiled spring having connection with the connecting rod, means at one end of the coiled spring to be positioned over the hook member, and means for permitting adjustment of the connecting rod with relation to 10 the body portion.

10 2. In combination, a washboard, an attachment including a hook member carried by the washboard, a body portion having a hook member adapted to engage the flanged bottom of a tub, a connecting rod adjustably connected to the body portion, and 15 resilient means for connecting the connecting rod to the hook member on the wash board for securing the washboard within the tub.

20 3. In combination, a washboard, a securing means including a body portion having a hooked end adapted to be positioned over the flanged bottom of a tub, said body portion having a plurality of openings 25 formed therein, a connecting rod having a hooked end adapted to be positioned within the openings, resilient means on one end of

the connecting rod, a hook member carried by the board, and means for connecting the resilient means and last mentioned hook 30 member.

4. In combination, a washboard, a securing means including a hook member supported by the washboard, a body portion, means for removably connecting the body portion to the flange of a tub, said body portion having a right angled apertured end, a connecting rod having a hooked member formed on one end thereof, said connecting rod adapted to pass through the aperture in the right angled end for securing the connecting rod to the body portion, resilient means having connection with the connecting rod, and means for connecting one end of said resilient means to the first 45 mentioned hook member.

In testimony that I claim the foregoing as my own, I have hereto affixed my signature in the presence of two witnesses.

GEORGE W. PELTON.
